UNITED STATES PATENT OFFICE.

WILLIAM W. HAWKINS, OF BROOKLYN, NEW YORK, ASSIGNOR TO WEBSTER ELECTRIC COMPANY, OF RACINE, WISCONSIN, A CORPORATION OF WISCONSIN.

IGNITION MAGNETO.

Application filed March 11, 1922. Serial No. 542,928.

My invention relates to a magneto adapted for ignition purposes, and contemplates the provision of an ignition magneto which embodies certain novel features of construction and functions in accordance with a novel plan or principle of operation which I shall hereinafter discuss in detail.

Since the general nature of my invention, as well as the details of my preferred embodiment thereof, will best be understood from a description read in connection with illustrative drawings, I shall proceed at once to a description of the accompanying drawings, in which:

15 Figure 1 is a vertical longitudinal section of my improved magneto.

Figure 2 is an end view of the magneto with one of the magneto end plates and the adjacent coil housing removed;

20 Figure 3 is a view similar to Figure 2, but illustrating the coil housing in position;

Figure 4 is an isolated elevational view of the inner side of one of the magneto end plates;

25 Figure 5 is an edge view of said end plate;

Figure 6 is an isolated end view in elevation of the structure in which the magnet pole pieces are mounted;

30 Figure 7 is a side elevational view of the structure shown in Figure 6;

Figure 8 is an isolated elevational view of one of the laminated structures which are carried with the coil housings;

35 Figure 9 is an edge view of the laminated structure illustrated in Figure 8;

Figure 10 is an end view of one of the coil housings;

40 Figure 11 is a side elevation of one of the coil housings;

Figure 12 is an isolated side elevational view of the magneto rotor, the rotor bearings being illustrated in section;

45 Figure 13 is an isolated end view of the rotor;

Figure 14 is a side view, partly in section and partly in elevation, of the interrupter housing, the interrupter being removed;

50 Figure 15 is an end view of the interrupter housing with its cap removed; and

Figure 16 is a circuit diagram.

Similar characters of reference refer to similar parts throughout the several views.

Referring now to Figure 1, at 20—20 I have illustrated a pair of superposed mag-

nets, the poles of which are in contact with laminated pole pieces 21—21. Said pole pieces are mounted in a non-magnetic frame 22, the metal of the frame being preferably cast or molded around the pole pieces. The frame 22 (see Figures 6 and 7) is provided at its sides with ledges 23—23 and 24—24 for engagement with the extremities of the magnets, and is provided at its ends with arcuate shoulders 25—25 and 26—26. The purpose of the shoulders 25—25 and 26—26 will presently appear. The frame 22 is further provided with a cylindrical bore 27, the wall of which is flush with the concave faces of pole pieces 21—21.

Located adjacent the ends of the frame 22 are the coil housings 28—28 which are formed of non-magnetic material. Each coil housing is provided with a bore 29 and an enlarged circular space 30 for the reception of one of the two generating windings 31—31. (See Figures 10 and 11 for the details of the coil housing.) Each coil housing is furthermore provided on that edge thereof next adjacent the frame 22 with annular rabbets 32, these rabbets being adapted to fit snugly around the shoulders 25 and 26 of frame 22 to prevent lateral displacement of the coil housing with respect to frame 22.

Carried by each coil housing 28, and preferably held in position by having the material of the coil housing molded or cast therearound, is a stationary core structure leg 33 which consists of magnetic laminæ. (For details see Figures 8 and 9.) Each laminated core structure leg is provided with a circular bore 34, the walls of bores 34 being in registry with the coil housing bores 29. Each core structure leg also comprises an upwardly extending portion 35 whereon rests one end of a laminated soft iron core 36, the ends of the core 36 being preferably screwed tightly to the upwardly extending portions 35 of the core structure legs. Core 36 carries a primary coil 37 and a secondary or high tension coil 38, the primary 37 being similar to the coils 31—31 in that it is formed of comparatively heavy wire, the secondary 38 comprising a relatively large number of turns of comparatively fine wire.

Referring again to the coil housings 28—28 (Figures 10 and 11), it will be noted that each of these housings is provided with an annular groove 39 in its outer end sur-

face, these grooves being concentric with bores 29 and being adapted to receive annular flanges 41-41 which are formed upon the inner faces of the magneto end plates 5 42 and 43. Bolts 44-44 tend firmly to clamp frame 22, coil housing 28 and the end plates 42 and 43 together.

The details of end plates 42 are clearly illustrated in Figures 4 and 5. The said 19 end plate is provided with a bore 45 for the reception of one of the trunnions of the hereinafter mentioned rotor, said bore being enlarged at its inner end for the reception 15 of the outer race of one of the ball bearings 46-46. It will be noted that bore 45 is formed in the outwardly projecting boss 47, the outer cylindrical surface of which is concentric with bore 45. The boss 47 receives the interrupter housing indicated at 48. End plate 42 is provided with a bore 49 into which is threaded an insulating bushing through which the insulated 20 terminal of the secondary coil 38 extends.

End plate 43 is generally similar to plate 25 42. Such differences as exists between the end plates will be readily apparent from an inspection of Figure 1.

Mounted for rotation in the ball bearings 46-46 are the trunnions 50 and 51 of a 30 rotor which also comprises a substantially cylindrical element 52 of non-magnetic material. The trunnions are preferably threaded and pinned in the ends of elements 52, as illustrated in Figure 12. Formed in element 52 are the diametrically opposite longitudinal slots 53-53 which extend from opposite ends of the member 52. Disposed in and fixed in each of these slots 53 is an inductor 54. Each inductor comprises a 35 plurality of soft iron laminae and is provided with a convex surface 54a which is concentric with the rotor axis.

Referring now to Figure 1, it will be seen that each inductor 54 at all times lies closely 45 to the wall of the bore 34 of one of the core structure legs 33. Each inductor also extends through, and is in inductive relation to, one of the coils 31-31. Each inductor is also adapted to sweep past the 50 magnet pole pieces 21-21 as the rotor operates.

At this time I call attention to the fact that a plate 55, end plates 42 and 43, the frame 22 and the coil housings 28-28 constitute a complete housing for the magnets and the primary and secondary coils 37 and 38. Plate 55 is preferably screwed to the end plates as shown.

Referring again to the interrupter housing 48 (for details see Figures 14 and 15), it will be noted that said housing is adjustably mounted upon the boss 47 of end plate 42, and is provided with a cap 56 which is preferably screwed upon the housing as shown. The interrupter housing is

held upon boss 47 by spring 57 which extends downwardly from a pin 58, which, in turn, projects from plate 42. The interrupter housing is preferably provided with a radially projecting handle for facilitating the adjustment of the housing to advance or retard the occurrences of the spark, as occasion may require. The interrupter housing comprises an inwardly projecting annular flange upon which is mounted the 70 suitably insulated block 59 which carries the fixed contact of the interrupter mechanism. Said fixed contact is electrically connected with a spring 60 which comprises a portion which bears against the head of a 75 screw 61. Screw 61 extends through, and is insulated from, the central portion of interrupter housing cap 56 (Figure 1). Screw 61 is connected by a suitable outside lead with the insulated side of the primary winding 37. At 62 is indicated the arm of the interrupter which is normally held with the contact thereof in engagement with the fixed contact. The usual spring associated with interrupter arm 62 is indicated at 63. The 80 usual two-point cam 64 serves to open the interrupter contacts twice during each revolution of the rotor. The interrupter contacts open at approximately the time that inductors 54-54 are leaving the magnet 95 pole pieces 21-21, the exact time that the contacts open being determined by the adjustment of the interrupter housing.

Referring now to the circuit diagram, it will be seen that one end of the primary winding 37 is connected with the stationary contact of the interrupter mechanism, the other end of said primary being grounded in the usual manner. Generating windings 31-31 are connected in parallel with each other and in shunt of the primary 37. I wish to point out, however, that windings 31-31 may be connected in series with each other if desired. One end of secondary 38 is grounded in the usual manner, the insulated terminal of the secondary being extended through the magneto end plate 42, as illustrated in Figure 1. I have not provided the magneto herein shown with the distributor, but in any case where my invention is utilized in connection with a multiple cylinder engine, the insulated secondary terminal will be connected with a distributor flyer in a well known manner. A condenser 65 is connected across the interrupter contacts. I find it convenient to mount the condenser in a recess 66 in the upper part of frame 20, as illustrated in Figure 1.

I will now describe the operation of the magneto. It will be understood that the inductors 54-54, core structure legs 33-33 and the core 36 constitute a low reluctance path for flux. The direction of the flux traversing this path is reversed each time the relation of inductors 54-54 to the mag-

net pole pieces 21—21 is changed, there being two reversals of flux through the inductor, core structure legs and the core 36 during each revolution of the rotor. The interrupter contacts separate twice during each revolution of the rotor, each separation of the contacts preferably occurring at approximately the instant that the trailing edges of the inductors are leaving the pole pieces.

Now let us assume that the rotor is in operation and that the inductors are about to leave the pole pieces. A current is generated in windings 31—31 and another current is generated in primary 37, but prior to the separation of the interrupter contacts, these currents do not interfere, since coils 31—31 are connected in parallel with winding 37 to ground, the two currents, due to the circuit connections, flowing in different directions through ground. As soon as the contacts open, however, the only path of the current generated in windings 31—31 includes winding 37, and, similarly, the only path for the current generated in winding 37 includes the windings 31—31. The two currents "buck", so to speak, and the most turbulent condition must exist in winding 37 for the fraction of a second, at least. This turbulent condition is augmented by the discharge of the condenser. Naturally the magnetic field threading the secondary 38 changes rapidly when the aforesaid turbulent electrical condition exists in the primary, and an exceptionally effective high tension ignition current is induced in the secondary 38.

The operation above described occurs twice during each revolution of the rotor of the particular machine herein shown and described.

Having thus explained what I believe to be a novel plan or principle of high tension magneto operation, and having illustrated and disclosed a preferred type of machine for carrying this plan or principle into effect, I do not limit myself to the specific construction and arrangement of parts herein shown and described, but wish to avail myself of all equivalent embodiments 50 of the invention set forth in the appended claims.

What I claim is new, and desire to secure by Letters Patent of the United States, is:

1. In a magneto, a rotor, magnet pole pieces, a coil, a core for said coil having extensions in proximity to said rotor, an inductor element on said rotor arranged to complete successive paths from said pole pieces to said core, and a fixed generator coil encircling said rotor between said pole pieces and said core extension.

2. In a magneto, a rotor, magnet pole pieces, a coil, a core for said coil having extensions in proximity to said rotor, inductor elements on said rotor arranged to

complete successive paths from said pole pieces to said extensions respectively, and generator coils encircling said rotor between said pole pieces and said extensions respectively.

3. In a magneto, a rotor, magnet pole pieces, a coil, a core for said coil having extensions in proximity to said rotor at the opposite ends thereof, inductor elements on said rotor arranged to complete successive paths from said pole pieces to said extensions respectively, and fixed generator coils encircling said rotor between said pole pieces and said extensions respectively.

4. In a magneto, a rotor, magnet pole pieces, a coil, a core for said coil having extensions encircling said rotor, inductor elements on said rotor arranged to complete successive paths from said pole pieces to said extensions respectively, and generator coils encircling said rotor between said pole pieces and said extensions respectively.

5. In a magneto, a rotor, magnet pole pieces, a coil, a core for said coil having extensions encircling said rotor at the opposite ends thereof, inductor elements on said rotor arranged to complete successive paths from said pole pieces to said extensions respectively, and generator coils encircling said rotor between said pole pieces and said extensions respectively.

6. In a magneto, a rotor, magnet pole pieces, a coil, a core for said coil having extensions in proximity to said rotor at the opposite ends thereof, inductor elements extending longitudinally of said rotor on the opposite sides thereof arranged to complete successive paths from said pole pieces to said extensions respectively, and generator coils encircling said rotor between said pole pieces and said extensions respectively.

7. In a magneto, a rotor, magnet pole pieces, a coil, a core for said coil having extensions encircling said rotor, inductor elements extending longitudinally of said rotor arranged to complete successive paths from said pole pieces to said extensions respectively, and fixed generator coils encircling said rotor between said pole pieces and said extensions respectively.

8. In a magneto, a rotor, a fixed generator coil encircling said rotor, magnet pole pieces, a coil, a core for said coil, an inductor element carried by said rotor arranged to complete paths from said pole pieces to said core, a circuit joined to the non-grounded sides of said coils in parallel, and an interrupter in said circuit.

9. In a magneto, a rotor, a fixed generator coil encircling said rotor, magnet pole pieces, a coil, a core for said coil, inductor elements on said rotor extending longitudinally thereof arranged to complete paths from said pole pieces to the ends of said core respectively, a circuit joined to the non-

grounded sides of said coils in parallel, and an interrupter in said circuit.

10. In a magneto, a rotor, magnet pole pieces, a coil, a core for said coil having extensions adjacent to said rotor, inductor elements on said rotor arranged to complete paths from said pole pieces to said extensions of said core respectively, stationary generator coils encircling said rotor between said pole pieces and said extensions respectively, a circuit joined to the non-grounded sides of said coils in parallel, an interrupter in said circuit, and a condenser in parallel with said interrupter.

11. In a magneto, a rotor, magnet pole pieces, a coil, a core for said coil having extensions in proximity to said rotor at the opposite ends thereof, inductor elements extending longitudinally of said rotor on the opposite sides thereof arranged to complete

successive paths from said pole pieces to said extensions respectively, fixed generator coils encircling said rotor between said pole pieces and said extensions respectively, a circuit joined to the non-grounded sides of said coils in parallel, and an interrupter in said circuit.

12. In a magneto, a rotor, a magnet having extensions disposed in proximity to said rotor, a coil, a core for said coil having an annular extension of magnetic metal surrounding said rotor adjacent one end thereof, and a fixed generator coil encircling said rotor between said magnet and core extensions and being electrically connected to said first named coil.

In witness whereof, I hereunto subscribe my name this 6 day of March, 1922.

WILLIAM W. HAWKINS.
